UNITED STATES PATENT OFFICE.

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF WISCONSIN.

LOCKING DEVICE.

Application filed December 18, 1926. Serial No. 155,628.

This invention relates to certain new and useful improvements in locking devices of that type especially designed for controlling a mechanism located remote from the key 5 actuated locking member, which heretofore has consisted of a mounting body or shell, a locking barrel mounting head having a lock bolt mechanism and being slidably mounted in the shell and having mechanism 10 to be locked connected therewith by a cable or the like and a tumbler cylinder rotatable in the locking barrel mounting head, the cylinder normally securing the mounting head fast in the mounting shell. 15 One of the objects of this invention is to materially simplify the key actuating locking mechanism by the elimination of the locking barrel mounting head and its lock bolt mechanism. 20 Another object of this invention resides in the provision of an improved locking mechanism wherein the tumbler cylinder is 25 slideable and rotatable within limits in the body or shell and controls the Bowden wire or other means connected with the element to be locked.

A further object of this invention resides in the provision of an improved locking mechanism of the character described, 30 wherein a helical or twisted member is carried by the tumbler cylinder to impart simultaneous longitudinal and rotary movement thereto in the shell when released by its key.

With the above and other objects in view which will appear as the description proceeds, my invention resides in the novel construction, combination and arrangement of parts substantially as hereinafter described 40 and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application 50 of the principles thereof, and in which:

Figure 1 is a view taken transversely through the locking device embodying my invention, illustrating the same in locked position, parts thereof being in section and 55 parts in side elevation;

Figure 2 is a view similar to Figure 1 illustrating the lock as in unlocked position with the body casing rotated through ninety degrees;

Figure 3 is a transverse, sectional view 60 through Figure 2 on the plane of the line 3-3, and

Figure 4 is a transverse, sectional view 65 through Figure 3 on the plane of the line 4-4.

Referring now more particularly to the accompanying drawing, in which like numerals designate like parts throughout the several views, 5 designates a body or shell member which may, for convenience and economy in manufacture, be die cast or machined from suitable metal, such as brass, and is adapted to be mounted at the instrument board or panel of an automotive vehicle when applied thereto. The rear portion 70 of the shell is bored or chambered, as at 6, and its forward portion is bored or chambered, as at 7, a plate or washer 8 being longitudinally movable in the bore 6 and has one end of a Bowden wire or other means 80 9 leading to the element to be locked, not shown, connected therewith, as at 10. An expansile spring 11 is confined between the washer 8 and a plug 12 is threaded into the inner end of the shell to close the bore 6 85 and through which the Bowden wire passes and to which a casing or tube 13 for the Bowden wire is suitably secured, as at 14.

The spring 11 normally exerts a pressure 90 on the washer 8 to tend to move the same into the bore 6 and with it the Bowden wire 9 to unlock the element, not shown with which the wire is connected and a key actuated means is mounted in the bore 7 to operate the washer against the 95 spring 11 and move the Bowden wire 9 to element locking position. The key actuated means consists of a plug or tumbler cylinder 15 which may be of substantially conventional construction having a series of tumblers 16 therein adapted to cooperate with a key 17, shown in dotted lines in Figure 1, which is adapted to be inserted in the key slot 18 of the cylinder and through the slots of the tumblers, the tumblers being urged 100 to engage in an elongated slot 19 in the shell 5 in register with the bore 7 by springs 20, best shown in Figure 3, to lock the cylinder against rotation. A slot 21 is formed in the shell 5 in communication with the bore 7 105 110

diametrically opposite the locking slot 19 to permit the ends 22 of the tumblers 16 to move thereinto when the key 17 is removed.

The cylinder 15 has its forward end portion 23 slightly reduced to pass through a bore of like diameter in a cap 24 secured over the flanged end 25 of the shell, the shoulder 26 formed at the inner end of the reduced portion 23 providing a stop abutting the cap 24 to limit the outward movement of the cylinder. The inner end portion 27 of the cylinder is preferably reduced in diameter and is slotted or recessed, as at 28, to receive the inner end of a tail piece 29 preferably formed from a length of metal having its outer end twisted to form a helical portion 30 which passes through a slot 31 in the partition or wall 32 supporting the bores 6 and 7. The tail piece is made fast to the cylinder end 27 by a rivet or screw 33 passing through an aperture in the end of the tail piece fitted in the slot 28 and threaded in the cylinder, as at 34, the tail piece imparting longitudinal movement to the cylinder as it is rotated by its key.

The tail piece 29 is so twisted that its ends are at approximately right angles to so define the limits of rotation of the cylinder and with the parts in the position illustrated in Figure 1, the element, not shown, with which the Bowden wire 9 is connected is in locked position. The key 17 is then inserted, the ends 22 of the tumblers moving into slot 21 as the key passes therethrough to unlocking position when the tumblers are drawn into the cylinder with their ends within the periphery thereof, as illustrated in Figure 3. The key 23 is then turned to rotate the cylinder, the tail piece assisted by the spring 11 moving the cylinder outwardly to its position shown in Figure 2, the spring 11 moving the washer 8 and the Bowden wire connected therewith into the shell to unlock the element, not shown, connected with the Bowden wire. When the cylinder is in its outermost or unlocked position, the key may be withdrawn if desired, a slot 35 in the wall of the shell 7 permitting the tumblers to move thereinto as the key is retracted.

To lock the device, the cylinder is pushed inwardly against the spring 11, the tail piece 29 rotating the same until it reaches its inward limit of movement when the tumblers align with the slot 19 and are moved therewith by their springs to lock the cylinder against movement in the shell. The cylinder is thereby locked against longitudinal movement by the helical member which structurally prevents such movement unless accompanied by a rotary movement.

The spring 11 being of strong construction to insure its operating the mechanism, not shown, connected with the Bowden wire 9, causes the cylinder to quickly move outwardly as the tumblers are retracted by the

key and this movement, assisted by the normal tendency of a person to twist the key when in place, is translated to a rotary movement by the helical member.

From the foregoing description taken in connection with the accompanying drawing, it will be readily apparent to those skilled in the art to which an invention of this character appertains that I provide a novel and improved locking device which is very efficient and practical in operation and which reduces the number of parts necessary for its operation, thus effecting a material economy in construction.

What I claim as my invention is:

1. In a lock of the character described, a bored stationary shell, a key actuated cylinder rotatably and slidably mounted in the shell bore, tumblers carried by the cylinder and engageable in a locking recess in the shell to normally lock the same in the bore, the cylinder being rotatable upon disengagement of the tumblers from their locking recess by a proper key inserted in the cylinder, a helical member, means securing the helical member to the cylinder, said helical member working in a slot in the shell whereby actuation of the tumblers by a key inserted in the cylinder and the rotation of the cylinder causes said helical member to impart longitudinal movement to the cylinder.

2. In a lock of the character described, a bored stationary shell, a key actuated cylinder rotatably and longitudinally slidably mounted in the shell bore, tumblers carried by the cylinder and engageable in a locking recess in the shell to normally lock the same in the shell bore, the cylinder being rotatable upon retraction of the tumblers from their locking recess by the insertion of a proper key, and a helical member carried by the cylinder and working in a slot in the shell whereby retraction of the tumblers and rotation of the cylinder causes said helical member to impart longitudinal movement to the cylinder.

3. In a lock of the character described, a stationary shell having its ends bored, a partition separating the bores of the shell, a key actuated cylinder rotatably and longitudinally slidably mounted in one shell bore, a helical member carried by the cylinder and extended through a slot in the partition and of a shape conforming with the cross-sectional shape of the helical member, key actuated means carried by the cylinder and engageable with the shell to prevent rotation of the cylinder, said cylinder being rotatable by a proper key inserted therein and rotation of the cylinder causing the helical member to impart longitudinal movement thereto, a washer member mounted in the other shell bore, means connecting the washer member with an element to be actuated, and spring means bearing against the washer member

to cause the same to follow the helical member, whereby movement of the cylinder outward of its bore causes the spring means to move the washer member into its bore and a reverse movement of the cylinder moves the washer member outwardly of its bore against its spring means.

4. In a lock of the character described, a stationary shell having its ends bored, a partition separating the bores of the shell, a key actuated cylinder rotatably and longitudinally slidably mounted in one shell bore, a helical member carried by the cylinder and extended through a slot in the partition of a shape conforming with the cross-sectional shape of the helical member, key actuated means carried by the cylinder and engageable with the shell to prevent rotation of the cylinder, said cylinder being rotatable by a proper key inserted therein and rotation of the cylinder causing the helical member to impart longitudinal movement thereto, a washer member mounted in the other shell bore, means connecting the washer member with an element to be actuated, spring means bearing against the washer member to cause the same to follow the helical member whereby movement of the cylinder outward of its bore causes the spring means to move the washer member into its bore and a reverse movement of the cylinder moves the washer member outwardly of its bore against its spring means, and a shoulder on the cylinder cooperating with the shell to limit outward movement of the cylinder.

5. A lock of the character described, comprising a normally stationary shell having a bore therein, a key actuated cylinder mounted in the shell bore and adapted to have si-

multaneous longitudinal and rotary movements therein, a locking element carried by the cylinder and normally locking the same in the shell and responsive to a proper key to free the cylinder of the shell, and means operable upon the unlocking of said element to effect the simultaneous longitudinal and rotary movement of the cylinder in the shell.

6. A lock of the character described, comprising a normally stationary shell having a bore therein, a key actuated cylinder mounted in the shell bore and adapted to have simultaneous longitudinal and rotary movements therein, a locking element carried by the cylinder and normally locking the same in the shell and responsive to a proper key to free the cylinder of the shell, and means operable upon the unlocking of said element to effect the simultaneous longitudinal and rotary movement of the cylinder in the shell within predetermined limits.

7. In a lock of the character described, a stationary shell having a bore therein, a key actuated cylinder rotatably and longitudinally slidably mounted in the shell bore, key actuated means carried by the cylinder and normally locking the same in the shell bore, the cylinder being rotatable upon the unlocking of the key actuated means by the insertion of a proper key in the cylinder, a helical member connected with the cylinder, and means cooperating with the helical member whereby the rotation of the cylinder causes the helical member to impart longitudinal movement to the cylinder.

In testimony whereof I hereunto affix my signature.

EDWARD N. JACOBI.

- to cause the same to follow the helical member, whereby movement of the cylinder outward of its bore causes the spring means to move the washer member into its bore and a 5 reverse movement of the cylinder moves the washer member outwardly of its bore against its spring means.
4. In a lock of the character described, a stationary shell having its ends bored, a partition separating the bores of the shell, a key actuated cylinder rotatably and longitudinally slidably mounted in one shell bore, a helical member carried by the cylinder and extended through a slot in the partition of a 10 shape conforming with the cross-sectional shape of the helical member, key actuated means carried by the cylinder and engageable with the shell to prevent rotation of the cylinder, said cylinder being rotatable by a 15 proper key inserted therein and rotation of the cylinder causing the helical member to impart longitudinal movement thereto, a washer member mounted in the other shell bore, means connecting the washer member 20 with an element to be actuated, spring means bearing against the washer member to cause the same to follow the helical member whereby movement of the cylinder outward of its bore causes the spring means to 25 move the washer member into its bore and a reverse movement of the cylinder moves the washer member outwardly of its bore against its spring means, and a shoulder on the cylinder cooperating with the shell to limit 30 outward movement of the cylinder.
5. A lock of the character described, comprising a normally stationary shell having a bore therein, a key actuated cylinder mounted in the shell bore and adapted to have si- 35
- multaneous longitudinal and rotary move- 40 ments therein, a locking element carried by the cylinder and normally locking the same in the shell and responsive to a proper key to free the cylinder of the shell, and means operable upon the unlocking of said element 45 to effect the simultaneous longitudinal and rotary movement of the cylinder in the shell.
6. A lock of the character described, comprising a normally stationary shell having a bore therein, a key actuated cylinder mounted 50 in the shell bore and adapted to have simultaneous longitudinal and rotary movements therein, a locking element carried by the cylinder and normally locking the same in the shell and responsive to a proper key 55 to free the cylinder of the shell, and means operable upon the unlocking of said element to effect the simultaneous longitudinal and rotary movement of the cylinder in the shell within predetermined limits. 60
7. In a lock of the character described, a stationary shell having a bore therein, a key actuated cylinder rotatably and longitudinally slidably mounted in the shell bore, key actuated means carried by the cylinder and 65 normally locking the same in the shell bore, the cylinder being rotatable upon the unlocking of the key actuated means by the insertion of a proper key in the cylinder, a helical member connected with the cylinder, and means cooperating with the helical member whereby the rotation of the cylinder causes the helical member to impart longitudinal movement to the cylinder. 70
- In testimony whereof I hereunto affix my 75 signature.
